(57) **CLAIM**

The ornamental design for a clitoral stimulation device, as shown and described.

DESCRIPTION

FIG. 1 is a perspective view of a clitoral stimulation device. FIG. 2 is a back view of the stimulation device assembly of FIG. 1.

FIG. 3 is a front view of the stimulation device assembly of FIG. 1.

FIG. 4 is a left-side view of the stimulation device assembly of FIG. 1.

FIG. 5 is a right-side view of the stimulation device assembly of FIG. 1.

FIG. 6 is a top view of the stimulation device assembly of FIG. 1; and,

FIG. 7 is a bottom view of the stimulation device assembly of FIG.
